(57) **CLAIM**

The ornamental design for a unitary elastomeric strap for use with a tablet computer, as shown and described.

DESCRIPTION

FIG. 1 is a top plan view of a unitary elastomeric strap for a tablet computer, the bottom plan view being a mirror image thereof;

FIG. 2 is a right-side elevational view thereof, the left-side elevational view being a mirror image thereof;

FIG. 3 is a front elevational view thereof, the rear elevational view being a mirror image thereof; and,

FIG. 4 is a perspective view thereof.
